(57) **CLAIM**

We claim the ornamental design for a strap tab, as shown and described.

DESCRIPTION

FIG. 1 is a right, rear perspective view of a strap tab showing the new design in a condition of use shown worn by a model; FIG. 2 is a right, front perspective view thereof; FIG. 3 is a front elevation view of the strap tab; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

In the drawings, the equal-length broken lines showing a mask, straps, and additional strap tabs depict unclaimed portions of the design. The equal-length broken lines in FIGS. 1 and 2 showing a human head depict environmental structure that forms no part of the claimed design. The dash-dot-dash lines of the strap tab peripheries define boundaries of the claimed design and form no part of the claimed design. All broken lines form no part of the claimed design.
